UNITED STATES PATENT OFFICE.

STEPHEN M. WALKER, OF OAK PARK, ILLINOIS.

CONTAINER.

Application filed September 3, 1921. Serial No. 498,293.

To all whom it may concern:

Be it known that I, STEPHEN M. WALKER, a citizen of the United States, and a resident of Oak Park, in the county of Cook and

5 State of Illinois, have invented certain new and useful Improvements in Containers, of which the following is a specification.

My invention relates to new and useful improvements in containers, and has for its 10 object to provide a container comprising a permanent outer member and a replaceable inner member carrying the material, and co-operating means on said members for forcing the material out of the inner member.

15 Another object is to provide a device of this kind which may be replenished by inserting a clean, full inner member for an empty one, thus enabling the user to dispense the material and refill the device without soiling his hands.

20 Other objects will appear hereinafter.

The device is especially adapted to contain and dispense lubricants used in the automobile industry, somewhat in the manner of a grease gun, but it is also very useful for containing and dispensing cold cream and any other plastic toilet articles. It is well adapted for use with plastic materials but is also very useful for holding and 25 dispensing liquid substances.

The invention consists in the combinations and arrangements of parts hereinafter described and claimed.

30 The invention will be best understood by reference to the accompanying drawings forming a part of this specification, and in which,

Fig. 1 is a sectional view of the device showing a threaded tube;

35 Fig. 2 is a modified view showing a smooth tube with a threaded end, the tube being shown partly in section;

Fig. 3 shows the casing in section, and the tube forced partly into the shell;

40 Fig. 4 is a view from the discharge end of the device shown in Fig. 1; and

Fig. 5 shows a modified manner of holding the neck of the tube against rotation in the cup of the casing.

45 The device or container consists of a permanent outer member or casing and a collapsible inner member or tube containing the material, and co-operating means on said casing and tube for forcing the material out of the tube.

50 The casing comprises a cylindrical mem-

ber or shell 10 which is provided with threads on the interior from the lower end to a short distance from the discharge or upper end thereof, the wall at this unthreaded upper portion 11 being made so as to provide an enlarged space 12 therein preferably in the form of an annular chamber. A laterally extending outer flange 13 is provided at the upper end of the shell 10 to engage an inwardly extending flange 14 on a sleeve 15. The sleeve 15 is threaded on the inside to engage threads on the outside of a cup 16, and the flange 13 of the shell is held between said cup and the flange 70 14 of the sleeve, whereby the shell 10 is held rotatably in position on said cup and sleeve. The external surface of the outer member or shell 10 has been shown smooth but may be of any suitable design or even 75 enclosed in a suitable ornamental covering.

The inner member or tube 18 is composed of pliable material such as tinfoil, pliable paper, or any suitable substance, and is provided with a threaded, rigid bottom member or cap 19 which is fastened into the lower end of the tinfoil of the tube in any convenient manner, so as to firmly adhere thereto, as shown in Fig. 1, or so as to form a substantially integral mass therewith, as 80 shown in Fig. 2. The surface of the tube may be threaded from top to bottom, as shown in Fig. 1, or may be threaded only the distance of the enclosed cap 19 and be smooth over the remaining distance, as 85 shown in Fig. 2. The cap is made rigid and preferably of metal whereby it stiffens the bottom of the tube and prevents the pliable material of the tube from collapsing at the lower end or stripping the thread, or taking 90 any other but the desired form, while the tube is being forced inward in the shell.

95 Means is provided for collapsing the tube 18 and forcing the material out of the tube through its neck 20. This means, in addition to the co-operating threads on the tube and in the shell, comprises a means of holding the tube against rotation in the cup 16, as by the use of threads on the neck 20 and in an opening 21 in the cup, as shown in 100 Figs. 1 to 4, or by providing an angular neck 22, and a similar angular opening 23 for receiving said neck, as shown in Fig. 5, or may be done by the use of pins or projections on the top of the tube which fit 105 in openings or depressions on the inner face of the cup, or in any convenient manner.

The threads on the neck 20 and on the cup 16 and the sleeve 15 are preferably right hand threads, while those on the cap and in the shell are left hand threads, and in either case the threads on the neck and cup and sleeve must be reversed to the threads on the cap and on the interior of the shell, in order that the tube will remain fixed on the cup while the shell is being rotated to collapse the tube and force the material out of it.

In the form illustrated in Fig. 2, the tube 18 is made smooth most of the way but is threaded along the distance of the cap 19 fitting closely over the threads of the cap and being rigidly or integrally fastened thereto.

In use, the tube 18, filled with the desired material, is placed in proper position in the shell 10 and the shell and the tube are threaded into the cup 16, whereupon the sleeve 15 is passed over the shell and threaded onto the cup 16; the sleeve and cup are then held in one hand, the tube remaining stationary therewith, while the shell 10 is rotated with the other hand, the interior threads on the shell thereby forcing the rigid threaded cap 19 into the shell, collapsing or folding the pliable tube 18, as shown at 24 in Fig. 3, in the enlarged space 12 provided at the upper end of the shell, thereby forcing the material out of the neck 20. The tube will in some cases also fold slightly along the threads in shell 10, but not sufficiently to hinder the inward travel of the rigid cap 19 or the discharge of the material during rotation of the shell, and will always and mainly fold or collapse at the enlarged space 12, as shown in the drawings. After the material has thus been forced from the tube, the tube will be removed and a new, filled one inserted, thus providing a containing and dispensing device especially adapted for use in the automobile industry, being also useful otherwise, which can be refilled and operated without soiling the hands.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent is:

1. A device of the class described comprising an internally threaded shell, means rotatably mounted therein, a tube fixed to said means, and threads on said tube and said

means co-operating with the threads on said shell for forcing said tube inward of said shell.

2. A refillable container of the class described comprising a shell provided with an open bottom and an annular inner chamber adjacent its upper end, a collapsible tube replaceably inserted through said open bottom into said shell, and means on said shell and said tube for rotating said shell with respect to said tube to collapse said tube in successive folds in said annular chamber and force out all the contents of said tube.

3. A device of the class described comprising a pliable tube having a rigid bottom, flanged means fastened to the upper end of said tube, a shell rotatably held by the flange on said means and provided with an enlarged space adjacent its upper end, and co-operating threads on said tube and shell whereby the tube may be collapsed in said space in the shell.

4. A device of the class described comprising a threaded cylindrical member with an open bottom and an enlarged annular chamber at its top, a collapsible tube replaceably inserted through said bottom, a substantially rigid cap attached to said tube and having threads co-operating with the threads of said member for collapsing said tube, and a cup mounted against rotation on the discharge end of said tube and to permit rotation of said cylindrical member with respect to said cup and tube for collapsing said tube entirely within said annular chamber.

5. A device of the class described comprising an inner member, a cup fastened directly to said inner member, a sleeve mounted on said cup to rotate therewith, an outer member rotatably mounted on said cup and sleeve, and threaded means on said outer and said inner members for forcing material out of said device by rotation of said outer member.

6. A device of the class described comprising an inner tubular member, a cup mounted against rotation on said tubular member, a sleeve mounted on said cup to rotate therewith, a shell rotatably mounted on said cup and sleeve, said shell being provided with an enlarged space at one end, and threaded means on said member and shell for collapsing said inner member in the enlarged space of said shell for forcing material out of said member by the rotation of said shell with respect to the other members.

In testimony whereof I have signed my name to this specification in the presence of two subscribing witnesses.

STEPHEN M. WALKER.
